(57) **CLAIM**

The ornamental design for an air treatment and portable dehumidifier unit as shown and described.

DESCRIPTION

FIG. 1 is a top, front, left perspective view of an air treatment and portable dehumidifier unit showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines showing portions of the air treatment and portable dehumidifier unit form no part of the claimed design.
